UNITED STATES PATENT OFFICE.

JAMES L. G. WEBB, OF GOODELLS, MICHIGAN, ASSIGNOR OF ONE-HALF TO ALBERT BAILEY, OF GOODELLS, MICHIGAN.

METAL SHOE.

1,216,896.

Specification of Letters Patent. Patented Feb. 20, 1917.

Application filed March 26, 1915. Serial No. 17,203.

To all whom it may concern:

Be it known that I, JAMES L. G. WEBB, a citizen of the United States, residing at Goodells, in the county of St. Clair and State 5 of Michigan, have invented certain new and useful Improvements in Metal Shoes; and I do hereby declare the following to be a full, clear, and exact description of the invention, such as will enable others skilled in the art 10 to which it appertains to make and use the same.

This invention relates to metal shoes, designed to be worn by miners and railroad section men, lumbermen, and others, and one 15 of the principal objects of the invention is to provide a shoe which may be slipped on over the ordinary shoe for protecting the sole, heel and toe portion of the shoe, or which may be formed as a shoe made of 20 metal and having a suitable lining to be worn without other shoes.

The foregoing and other objects may be attained by means of the construction illustrated in the accompanying drawing, in 25 which,

Figure 1 is a side elevation of a metal shoe adapted to be worn over the ordinary shoe and made in accordance with this invention,

Fig. 2 is a side elevation of a metal and 30 leather shoe adapted to be worn next to the stocking,

Fig. 3 is a bottom plan view of the metal sole,

Fig. 4 is a longitudinal sectional view 35 through the shoe shown in Fig. 1,

Fig. 5 is a longitudinal sectional view through the shoe shown in Fig. 2, and

Fig. 6 is a detail sectional view showing 40 the manner of securing the calks to the metal sole.

Referring to the drawings, and more particularly to Figs. 1 and 4 thereof, the numeral 1 designates the ordinary shoe worn by miners, railroad section men, or lumbermen, and this shoe may be of any suitable type. The metal overshoe comprises a toe cap 2, a heel stiffener or counter 3 and a heel portion 4, said heel portion being of greater thickness than the counter, as shown in Fig. 45 1, and adapted to receive the heel 5 of the shoe 1. In this type of shoe, an instep strap 6 extends around the shoe and is connected to one side of the metal counter 3, while at

the other side a tab or strap extension 7 is connected by suitable fastenings 8 and a buckle 9 connects the strap 6 and the extension 7, to hold the metal shoe firmly in place on the shoe of the wearer. Immediately in front of the heel 5 the metal plate is hinged at 10 and side flanges 11 are turned up over 60 the sides of the sole. A hinge member 12 is also connected to the hinge 10 and to a similar hinge 13 so as to give an elastic movement at the shank of the shoe. The sole portion 14 of the shoe extends around 65 and is formed integral with the cap 2.

The overshoe may be made of copper, steel, aluminum, or any other suitable metal, and at the sides of the sole flanges 11 extend up beyond the thickness of the sole of the inner 70 shoe. Calks 15 for the sole and heel of the shoe are provided with threaded shanks 16 and may be connected at any suitable point in the sole and heel of the shoe, said calks being particularly desirable for lumbermen 75 and others working in cold climates and on slippery places.

The shoes shown in Figs. 2 and 5 are substantially the same as that already described excepting that there is no instep strap used, 80 and the leather upper 1^a of the shoe is connected by a line of fastenings 2^a to the metal counter 3^a and the remaining portion of the metal sole and toe caps are substantially the same as that already described. 85

From the foregoing it will be obvious that a shoe made in accordance with this invention will wear four or five times as long as the ordinary leather shoe, and will be perfectly safe for persons working on ice or on 90 slippery places.

Various changes may be made in the details of construction without departing from the spirit and scope of the invention as defined in the claim. 95

What is claimed is:—

A metallic overshoe comprising an arch plate section having the ends thereof converged toward one side, a heel plate section having an extension on the breast portion 100 thereof, and a sole plate section, upwardly extending flanges formed on the edges of said sections, the upwardly extending flanges on the ends of the arch plate being slit, thus forming tongues, said tongues being rolled, 105 the flanges formed on the inner end of the

breast portion of the heel section and the inner end of the sole plate section being slit and rolled, pins connecting the rolled tongue portion of said breast plate on the heel section, arch plate section and said sole plate section, and means for securing the over-
5 shoe to the foot of the wearer.

In testimony whereof I affix my signature in presence of two witnesses.

JAMES L. G. WEBB.
